RIVET REMOVER FOR ROLLER CHAINS

George A. Arnett and Richard E. Lanning, Wichita,
Kans., assignors to Rains Manufacturing Company,
Inc., Newton, Kans., a corporation of Kansas

Filed Mar. 14, 1960, Ser. No. 59,712

Term of patent 14 years

(Cl. D54—13)

Fig. 1.

Fig. 2.

Fig. 3.

Fig. 5.

Fig. 4.

FIG. 1 is a top plan view of a rivet remover for roller chains, showing our new design;

FIG. 2 is a side elevational view thereof;

FIG. 3 is a bottom plan view thereof;

FIG. 4 is an end elevational view taken from the left side of FIG. 2 with a chain element shown in broken lines for the purposes of illustration only; and

FIG. 5 is a sectional view taken on line 5—5 of FIG. 2.

We claim:

The ornamental design for a rivet remover for roller chains, as shown and described.
